RADIOTELEGRAPH RECEIVER

Percival D. Lowell, Chevy Chase, Md.

Application September 11, 1937, Serial No. 163,461

7 Claims. (Cl. 250—8)

My invention relates broadly to radiotelegraph receiving systems and more particularly to printing telegraph circuits wherein signal pulses in two tones are utilized for operating printing mechanism.

Where printing telegraph receivers are installed in connection with systems employing two-tone modulation at the transmitters, it is only necessary to provide at the receivers selective circuits adapted to the two-tone modulation employed. Many transmitters, however, emit signals constituted as a carrier wave modulated by only a single tone in on-off fashion, making up the signal in combinations of pulses and spaces. Ordinarily it is not possible to operate printer mechanism requiring two-tone signals by any other type of modulated wave.

One of the objects of my invention, therefore, is to provide an arrangement for simulating two-tone modulation in the output of a radiotelegraph receiver when the signal input is of the single tone, on-off modulated type.

Another object of my invention is to provide a tone generator operative at a frequency different from the tone frequency of modulation in the received signal and means for impressing the output of such generator on the carrier wave in the intervals between the modulations thereof in order to produce the effect of two-tone modulation of the carrier.

Still another object of my invention is to provide, in a superheterodyne type of receiver, means for modulating the output of the conversion oscillator at a tone frequency different from the frequency of the modulation in the signal received, in the intervals between recurring signal pulses.

A further object of my invention is to provide a radiotelegraph receiver for single tone modulated signals with two-tone signal output circuits, and means for supplying a second tone signal intermediate pulses of the signal modulations received.

Other and further objects of my invention reside in the circuits and arrangements herein-after set forth with reference to the accompanying drawing which shows by way of example a schematic diagram of my invention as applied to the superheterodyne type of radiotelegraph receiver. The drawing schematically illustrates such receiver in outline only, and it will be understood that the various related elements known in the art may be added thereto.

My invention is directed to a printing telegraph system whereby the signal pulses are ob-

tained by starting and stopping the audio frequency modulation of the transmitter carrier wave. Two-tone effect at the receiving end using only one on-off tone at the transmitter can be attained using my invention at the receiving station. In carrying out my invention it is assumed for example that the modulation frequency at the transmitter is 1000 cycles and that a superheterodyne type of receiver is employed at the receiving station. Provision is made for modulating the frequency converting oscillator at a frequency of, for example, 1500 cycles, by means of an external audio frequency tube generator. Following the circuit through, where a "mark" impulse is being transmitted, the carrier is modulated at 1000 cycles and the received signal goes through the receiver in a normal manner, through an audio frequency 1000 cycle band pass filter and rectifier. The output of the rectifier is fed to one winding of a polarized relay and causes the armature to pull to the marking side. The output of the rectifier is also fed into the grid return circuit of the 1500 cycle audio frequency tube generator in such a way that the grid becomes highly negative causing the circuit to stop oscillating. Then the frequency converting oscillator is not modulated. When the 1000 cycle modulation of the transmitter is removed for a "space" impulse, there will be no 1000 cycle signal to go through the 1000 cycle filter and therefore no direct current flow in the output of the rectifier and the relay will be unenergized and the negative cut-off bias removed from the 1500 cycle audio frequency tube generator, allowing it to oscillate. Therefore simultaneously, the frequency converting oscillator becomes modulated at 1500 cycles, combines with the incoming unmodulated signal carrier and a 1500 cycle audio frequency signal will pass through the 1500 cycle band pass filter, be rectified, and excite the relay winding in an opposing direction, causing the armature to pull over to the spacing position.

Referring more particularly to the drawing, I have shown first a radio frequency amplifier stage 3 fed from the antenna circuit 1 through resonant circuit 2. The output circuit of the high frequency conversion oscillator 4 is coupled together with the output circuit of the amplifier 3 to the input of the converter of first detector stage 5. The output of the converter at intermediate frequency is fed to the second detector stage 6. The foregoing broadly states the elements of the superheterodyne receiver as disclosed.

In the output of the second detector would appear normally, with single tone modulated signals, recurring pulsations in the signal code and of the tone employed for modulation, a tone of, say, 1000 cycles. Accordingly selective filter and amplifier circuits are provided at 7 coupled with the second detector 6 and connected with one winding 8a of the polarized relay 8 through a rectifier device 9. The relay 8 will be operative, however, only in one direction, with the recurring signal pulses at 1000 cycles.

In order to operate the relay 8 properly, as with two-tone signal transmission, I provide an audio frequency oscillator circuit 10 arranged to 15 modulate the output of the high frequency conversion oscillator 4 at say, 1500 cycles, and selective filter and amplifier circuits 12 coupled with the second detector 6 and connected with the other winding 8b of the polarized relay 8 through a rectifier device 14. The winding 8b of the relay will thus be energized in accordance 20 with the operation of the audio frequency oscillator 10 which supplies the 1500 cycle signal.

As the presence of the 1500 cycle tone is desirable only in the absence of the 1000 cycle signal pulses in order to simulate accurately the two-tone modulation required to effect proper operation of the polarized relay 8, I provide connections 15 from the output of the rectifier 9 to 25 supply a cut-off potential in the grid circuit of the audio frequency amplifier 10, as illustrated, when current flows in the circuit of rectifier 9. In the absence of such current, which is the condition between 1000 cycle signal pulses, the audio 30 frequency oscillator circuit 10 has correct operative potentials supplied thereto and accordingly functions to provide a 1500 cycle signal which results in a current flowing in the circuit of rectifier 14 and winding 8b of the polarized 35 relay.

In the absence of a carrier wave resonant in circuit 2, the output of audio frequency oscillator 10 continuously modulates the conversion oscillator 4; but as the frequency of the oscillator 4 differs from the intermediate frequency of the superheterodyne system, the modulated output of the oscillator is confined to the circuits of the first detector stage 5 and no current will appear in the circuit of rectifier 14, and winding 50 8b of the relay. This is a distinct advantage of my system obtainable in the superheterodyne type of receiver as disclosed.

The system of my invention is adaptable to various types of receiving circuits as will be understood by those skilled in the art. For example, the 1500 cycle signal may be produced as a beat note between the local high frequency oscillator and the carrier wave of the received signal, the local oscillator being under the control 55 of the signal modulation of the carrier, as hereinbefore described with reference to the oscillator 10; in a superheterodyne receiver, this high frequency oscillator may beat with the intermediate frequency wave and thus be stabilized at a selected frequency.

Furthermore, in continuous wave reception, I may provide a high frequency beat oscillator for producing with the continuous signals an audible beat of say, 1000 cycles, and an audio 70 frequency oscillator for, say 1500 cycles arranged to oscillate under control of the received signals. In continuous wave reception however, the audio frequency oscillator may constantly supply current to one winding of the relay when not controlled by the beat note, due to the complete

cut-off of the carrier between pulses of the continuous wave signals.

Thus while I have described my invention in a preferred embodiment, I desire it understood that modifications may be made in the type of 5 circuit and the circuit arrangements, and that no limitations are intended, therefore, except as imposed by the scope of the appended claims.

What I claim as new and desire to secure by Letters Patent of the United States is as follows:

1. A radiotelegraph receiving system comprising circuits tuned to resonance with an incoming signal wave, a detector circuit connected with said tuned circuits and having selective circuits coupled therewith, one of said selective circuits being adapted to pass currents of the frequency of modulation of the incoming signal wave, means coupled with said tuned circuits for introducing currents of a different frequency 20 for passing which another of said selective circuits is adapted, and means energized from the first said selective circuit for controlling the operation of the aforesaid means in accordance with the signal current. 25

2. A radiotelegraph receiving system adapted to provide two-tone signal output from a single tone modulated signal input, comprising circuits for detecting the single tone modulated signal input and a selective circuit coupled thereto for 30 passing currents of the frequency of modulation, means for introducing a second tone signal into said circuits for detecting, a separate selective circuit coupled to said circuits for detecting and adapted to pass currents of said second tone 35 signal, and means energized from the first said selective circuit for controlling the operation and inoperation of the aforesaid means respectively with the absence and the presence of signal currents in the first said selective circuit. 40

3. A radiotelegraph receiving system adapted to provide two-tone signal output from a single tone modulated signal input, comprising circuits for detecting and selectively passing the single tone signal modulations, and means connected 45 with said circuits for producing a second tone signal in the time intervals between the single tone modulations, said single tone and said second tone signals in conjunction constituting in effect a two-tone signal output. 50

4. A radiotelegraph receiving system including dual selective circuits at the output thereof adapted for two-tone signal output, local means for producing signals of one tone directly coupled with said receiving system, and means responsive to received signals of the other tone for limiting the operation of said local means to provide signals of the one tone for said two-tone output in the absence of signals of the other tone. 55

5. A superheterodyne telegraph receiving system including conversion oscillator, first and second detector circuits, dual selective circuits coupled with the second detector circuit adapted for two-tone signal output, means for modulating 65 said conversion oscillator circuit for producing signals of one tone, and means responsive to received signals of the other tone for limiting the operation of said modulating means to provide signals of the one tone for said two-tone signal 70 output in the absence of signals of the other tone. 60

6. A superheterodyne radiotelegraph receiving system including conversion oscillator, first and second detector circuits, dual selective circuits 75

coupled with the second detector circuit and adapted for two-tone signal output, a low frequency oscillator coupled with said conversion oscillator for modulating the output thereof at the frequency of one of said selective circuits, and means for controlling the operation of said low frequency oscillator in accordance with current conditions in the other of said selective circuits.

7. A radiotelegraph receiving system as set forth in claim 5 and including a heterodyne oscillator modulated by said local means, a first

detector, and intermediate selective circuits responsive at the beat frequency of the heterodyne oscillation and a received carrier wave in said first detector, whereby the signals of the one frequency produced by said local means are transmitted to the respective selective output circuit with the cooperation of said received carrier wave and are not effective in said output circuit in the absence of the carrier wave.
